UNITED STATES PATENT OFFICE

CHARLES R. DRAKE, OF ROCHESTER, NEW YORK, ASSIGNOR TO THE LINE-A-TIME MFG. CO. INC., OF ROCHESTER, NEW YORK, A CORPORATION OF NEW YORK

COPYHOLDER FOR BILLING MACHINES

Application filed April 2, 1927. Serial No. 180,483.

This invention relates to copyholders of the type in which a copy plate and a line indicator spanning the copy plate are moved relatively to each other by mechanical means, 5 and particularly to a copyholder which is adapted for use with billing or tabulating machines and the like.

The ordinary form of copyholder is adapted to be mounted behind the machine with 10 which it is being used on the table or desk, or other support upon which the machine is mounted, and to have its operating lever extending to a point in front of the machine within easy reach of the operator. Such a 15 manner of use is entirely satisfactory when the machine is an ordinary typewriter; however, some billing and tabulating machines are of such length that if the copyholder is placed behind the machine it is usually difficult for the operator to read the subject 20 matter being copied. Also, much of the subject matter to be copied by operators of billing and tabulating machines is printed or written on relatively small cards or sheets 25 of paper which the ordinary type of copyholder is not adapted to handle satisfactorily.

An object of this invention is to provide a copyholder of strong and durable construction which may be conveniently used in connection with billing machines and the like. 30 Another object is to provide improved means for supporting a copyholder in an operative position relatively to a billing machine or the like. Another object is to provide an improved attachment by means of which a copyholder may be readily adapted to handle small cards or sheets satisfactorily. Another 35 object is to provide improved means for operating a copyholder. Other objects will be in part obvious or in part pointed out hereinafter.

In the accompanying drawings in which is shown one of the various possible embodiments of this invention,

45 Figure 1 is a front elevation of the copyholder applied to a billing machine;

Figure 2 is a side elevation similar to Figure 1;

50 Figure 3 is a rear elevation of the copyholder; showing the supporting frame and

the base which is adapted to support the billing machine;

Figure 4 is a plan view of the supporting base;

Figure 5 is a plan view of the foot treadle; 55

Figure 6 is a view taken substantially on line 6—6 of Figure 1;

Figure 7 is a sectional view of the card receptacle; and

Figure 8 is a sectional view of the means 60 for locking the card receptacle in position on the copyholder.

Similar reference characters refer to similar parts throughout the several views of the drawings. 65

Referring now to the drawings in detail, there is shown a base comprising a substantially rectangular body portion 10 having arms 11 projecting from one side, and provided on its upper surface with recesses 12 70 for the reception of the supporting legs of a billing machine or the like. Discs 13 of rubber or other soft material are attached to the lower face of the base for the purpose of spacing the said base from the table or desk or other support upon which it is mounted. Two leg members 14 are mounted on each side of the base adjacent the end thereof and form brackets or supporting arms upon which the supporting frame 15 is rigidly mounted. 75

The frame 15 may be best described as comprising two substantially U-shaped members 16 and 17 rigidly connected together in such a manner that the leg portions of one member extend inwardly toward the leg portions of the other member and the bottom portions 20 and 21 of the U's extend substantially parallel to each other. The U-shaped members each have a leg portion attached to the upper end portion of a bracket 80 formed by the supporting members 14, and extend outwardly beyond the opposite side edges of the base. The bottom portions 20 and 21 of the U's extend substantially vertically and the other legs of the U-shaped members extend substantially horizontally inwardly and are rigidly connected together. 85

The portion 20 of the U-shaped member 16 is longer than the portion 21 of the member 17, consequently, the upper leg of the mem- 90
95
100

ber 16 is spaced farther from the base than the upper leg of the member 17. Thus, substantially one-half of the upper portion of the frame 15 is spaced above the other half, 5 and loops of different sizes are provided on opposite sides of the frame.

A copyholder 22 is rigidly mounted on the upper leg of the U-shaped member 17 by means of screws or bolts 28 and a brace 10 29. The copyholder is provided with the usual essential parts, such as a casing plate 23, copy plate 24, line indicator 25, paper holding clip 26, clutch rod 27, clutch member 30, lifting rod 31, actuating lever 32, 15 and suitable guide rods and holding and retarding mechanisms not shown. The actuating lever 32 is operatively connected with the lifting rod and casing plate in the usual manner, and its outer end extends beyond a 20 side edge of the copyholder and is pivotally attached to an end of an adjustable connecting rod 33 which is pivotally attached adjacent its other end to a foot treadle 34. The connecting rod 33 comprises two substantially identical portions which may be 25 of the same length or of different lengths, and each of which has a threaded end portion. One of said end portions is provided with right hand threads and the other with 30 left hand threads, and a suitably threaded sleeve 35 having a wing nut 36 rigidly mounted thereon, is mounted on the said end portions and provides means for adjusting the length of the rod 33.

35 The treadle 34 is pivotally attached intermediate its ends to a bracket 37 which is adapted to be mounted on the floor. Foot pedals 40 and 41 are mounted on the treadle on opposite sides of the bracket 37. Thus 40 by pressing down on the pedal 41 the actuating lever 32 may be moved upwardly to operate the lifting rod and thus raise the copy plate in the usual manner, and by pressing down on the pedal 40, the actuating lever 45 may be moved downwardly to release the lifting rod holding means in the usual manner and thus permit the copy plate to move downwardly to its normal position.

To provide for the satisfactory handling 40 of small cards or sheets there is provided a substantially rectangular receptacle 42 having an open top for the insertion and withdrawal of the cards. The receptacle is formed in such a manner that there is an 45 opening in the front wall through which the written or printed matter is visible, and the line indicator is adapted to cooperate with the cards in the usual manner. The receptacle is preferably formed from a blank of sheet metal bent to form a rear wall 43, side walls 44, side flanges 45, a bottom wall 46, and a bottom flange 47. The flanges 45 and 47 are turned inwardly and form stop members for confining the cards within the receptacle. The rear wall is longer than the

front flanges 45 and the side walls are preferably beveled downwardly from a point adjacent the top of the rear wall to the tops of the flanges 45. For attaching the receptacle 42 to the copy plate 24, there is provided a supporting member 50 attached to the outer face of the rear wall and having arms 51 projecting rearwardly from its opposite ends. One of the arms 51 is provided with a central bore in which is mounted the rounded head portion of a rubber button 52. The member 52 has a circular base portion of greater diameter than the head portion, the outer face of which normally bears upon a side flange of the copy plate 24. The other 75 arm 51 has a thread bore or slot adjacent its outer end in which is mounted a screw 53. A rectangular plate 54 having a rubber button 52 mounted in an aperture therein is swiveled on the inner end portion of the screw 53 in such a manner that the base of the button 52 is adapted for contact with the other side flange of the copy plate 24. One straight edge of the rectangular member 54 is normally held in contact with the 80 rear face of the copy plate 24 and the rectangular member is thus held against rotation. The card receptacle may be placed in any desired position on the copy plate by simply causing the arms 51 to embrace the 85 copy plate in such a manner that the outer face of the supporting member 50 is substantially in contact with the front face of the copy plate, and then turning the screw 53 until the rubber buttons 52 bind upon the sides of the copy plate. The provision 90 of rubber buttons permits the receptacle to be securely held in place and prevents displacement incidental to the frequent jarring of the copy plate.

The base and frame are preferably of such sizes that when a billing machine is mounted on the base, the lower portions of the frame are substantially in contact with the sides of the machine, intermediate the ends thereof, and the looped portions provide clearance for the sliding carriage of the machine. The larger loop is preferably of such a size that the operator may pass a hand therethrough to the levers at the rear of the machine. The copyholder may be mounted upon the upper leg of the smaller loop portion with its lower end immediately adjacent the top of the machine. Thus, the copyholder is positioned in such a manner relatively to the operating position of the operator that the subject matter mounted thereon is easily readable. The machine serves to aid in holding the copyholder steadily in position. The provision of a foot treadle for operating the copyholder eliminates the necessity for the usual hand operated lever and permits the operator to have free use of both hands for operating the machine, shifting cards in the card receptacle, and the like.

From the foregoing it will be seen that there is herein provided apparatus which embodies the features of this invention and achieves the objects thereof, including many practical advantages. Copy supporting apparatus has been provided which is thoroughly efficient and dependable in use and by means of which written or printed matter to be copied is supported in such a manner that it may be easily read by a machine operator.

As many possible embodiments may be made of the above invention, and as many changes might be made in the embodiment above set forth, it is to be understood that all matter hereinbefore set forth or shown in the accompanying drawings is to be interpreted as illustrative and not in a limiting sense.

I claim as my invention:

1. A copyholder supporting frame comprising a pair of spaced brackets, a substantially U-shaped member mounted on each of said brackets with the bottom portions of the U's extending substantially vertically and the leg portions extending inwardly, and means connecting the upper leg of one U-shaped member with the upper leg of the other U-shaped member; the bottom portion of one of said U's being longer than the bottom portion of the other U.

2. An attachment for copyholders comprising a receptacle having spaced side arms mounted thereon for engaging the sides of a copy plate, and relatively soft cushioning means mounted on said side arms for gripping cooperation with said copy-plate.

3. An attachment for copyholders comprising a substantially rectangular receptacle, a supporting member mounted on said receptacle adjacent an end thereof, side arms mounted on said supporting member adjacent the ends thereof and extending substantially at right angles thereto, and an adjusting member mounted on one of said side arms.

4. An attachment for copyholders comprising a substantially rectangular receptacle having the central portion of its front wall removed, a supporting member mounted on the rear wall of said receptacle adjacent an end thereof, side arms mounted on said supporting member adjacent the ends thereof and extending rearwardly of the rear wall of said receptacle, and an adjusting member threaded in one of said side arms.

5. In combination, a copyholder having a support, a line indicator on the support, a copy-plate movable on said support relative to said line indicator, and a card holder mounted on said copy-plate and movable therewith relative to the line indicator, said holder being adapted to support a card for movement relative to and in cooperation with said line indicator.

6. In combination, a copyholder having a support, a line indicator on the support, a copy-plate movable on said support relative

to said line indicator, and a card holder detachably mounted on said copy-plate and formed with guideways for slidably receiving and supporting a card for movement with the copy-plate relative to said line indicator.

7. An attachment for copy-plates of copyholders, comprising a card holder formed of a plate member having flanges on the side and lower edges for receiving and supporting a card, arms on said plate member adapted to embrace said copy-plate, and means carried by said arms for detachably securing said arms to said copy-plate.
